G. E. PARKS

LOCOMOTIVE FRAME

Filed Aug. 21, 1922

UNITED STATES PATENT OFFICE.

GEORGE E. PARKS, OF DETROIT, MICHIGAN.

LOCOMOTIVE FRAME.

Application filed August 21, 1922. Serial No. 583,218.

To all whom it may concern:

Be it known that I, GEORGE E. PARKS, a citizen of the United States, residing at Detroit, county of Wayne, and State of Michigan, have invented a certain new and useful Improvement in Locomotive Frames, of which the following is a full, clear, and exact description, such as will enable others skilled in the art to which it appertains to make and use the same, reference being had to the accompanying drawings, forming part of this application.

My invention relates to railroad rolling stock and consists in an improved locomotive frame construction especially adapted for use in one-piece cast frames. It is customary to form the top and bottom rail members and the pedestal jaw members integrally of practically rectangular section, uniform in areas in an attempt to secure uniform strength. After the casting is produced, the frame is drilled horizontally and vertically at different points to provide for the attachment of various other locomotive parts to the frame. This perforation of the frame reduces the cross sectional area so that the uniform strength for which the casting is designed is not present in the finished product when it is assembled with the other locomotive parts.

The object of my invention is to produce a frame, the cross sections of which at various points will vary in shape and overall height and depth, but will be substantially constant in cross sectional area where desired, without including the open spaces produced by the drilling of bolt and rivet holes, etc.

In the accompanying drawings, which illustrate a selected embodiment of my invention,—

Figure 1 is a side elevation of my improved locomotive frame.

Figures 2 to 13 inclusive are transverse sections taken on the lines 2—2, 3—3, etc., of Figure 1.

The lefthand portion of the frame illustrated is provided with an upper rail 1 which extends over the pedestal openings and with a lower rail 2 which extends between the pedestal openings and at the right merges with rail 1 to form the cylinder connecting portion 3 of the frame. That portion of rail 1 over the pedestal openings is rectangular in cross section, as shown in Figure 2. The portion between the rail openings is of in-

verted U-section and the inclined portion at the right of the pedestal opening is similarly shaped but provided with additional flanges, where necessary, to maintain the desired cross sectional area, which is substantially constant at these different points.

The lower rail 2 is U-shaped in cross section and merges into the vertical portions 3 at the sides of the pedestal openings without substantial change in shape or sectional area. It will be noted that various horizontal openings 4 and vertical openings 5 are provided in the different walls of both of these rails which, if drilled through a section otherwise unchanged, would reduce the area and strength at different points. To compensate for this reduction, the walls of the casting are thickened at these points throughout their length or by suitable bosses 75 so that the cross sectional area is not affected. In other words, the area of the figures shown in Figures 3 and 4 is substantially equal although the contour is the same and the openings therethrough are at right angles to each other. By locating the bosses surrounding the openings 4 and 5 in these two figures on the inside faces of the casting walls, the exterior contour is not affected and the appearance and outside clearance of a frame is the same as in the ordinary construction.

Similarly, Figures 5, 6, 7 and 8 show the different shaping and perforation of lower rail 2 and vertical portion 3 without substantial variation in cross section area.

At the right of the pedestal openings, the upper rail is increased in sectional area and a depending flange 6 is provided for a short distance, as shown in Figures 1 and 9. Immediately beyond this portion of the casting, an upstanding flange 7 is provided in place of flange 6 without varying the area of the rail.

Where the rails are united in the cylinder connecting portion of the frame, the sectional area is greater than either rail 1 or rail 2, but less than the combined areas of these rails, as shown in Figures 11 and 12, but throughout the length of this portion of the frame the area is maintained constant, although this part of the frame is freely perforated with transverse holes 8.

While different locomotives will require different designs of frames and various equipment will necessitate sectional adaptation of the adjacent portions of the frame

thereto, it is obvious that that shape and thickness of the wall can be varied to maintain the sectional area as illustrated in the accompanying drawings.

5 I contemplate such modifications in the contour and cross section of the frame as may be required for different installations, without departing from the spirit of my invention as expressed in the appended claims.

10 I claim:

1. A one-piece cast locomotive frame having pedestal openings and including a single rail portion over the pedestal openings and spaced parallel rail portions intermediate the 15 pedestal openings, said single rail portion being box-shape in cross section and said intermediate rail portions being U-shape in

cross section, the thickness of the walls of the casting varying in differently shaped cross sections so that the sectional areas of 20 said box and U-shaped portions are substantially equal.

2. A one-piece cast locomotive frame having pedestal openings and including a single rail portion over the pedestal openings and 25 spaced rail portions intermediate the pedestal openings, said single rail portion and said intermediate rail portions being of different shaped cross sections, the walls of said cross sections varying in size so that their sectional areas are substantially equal.

30 In testimony whereof I hereunto affix my signature this 11th day of Aug., 1922.

GEORGE E. PARKS.
